& CO., OF NEW YORK, N. Y.

DESIGN FOR A CARPET-PATTERN.

Specification forming part of Design No. 5,896, dated June 4, 1872.

To all whom it may concern:

Specification describing a new and original Design for a Carpet, invented by DAVID PATON, of Halifax, in the county of York, England.

The accompanying photograph fully illustrates my invention.

The circular center of the main figure of this design is surrounded by a curvilinear figure, which forms six projections, and under which another six-pronged figure, with spear-heads

at the four main prongs, is drawn. A square frame surrounds the above, and is ornamented in its border with rosettes, as shown, and placed on a ground of gracefully-curved scrolls.

I claim as my invention—

The design for a carpet, as shown.
